UNITED STATES PATENT OFFICE.

JOSEPH W. PHINNEY, OF MEDFORD, MASSACHUSETTS.

DESIGN FOR A FONT OF TYPE.

SPECIFICATION forming part of Design No. 30,253, dated February 21, 1899.

Application filed December 30, 1898. Serial No. 700,768. Term of patent 7 years.

To all whom it may concern:

Be it known that I, JOSEPH W. PHINNEY, of Medford, in the county of Middlesex and State of Massachusetts, have invented and 5 produced a new and original Design for a Font of Type, of which the following is a specification.

This design comprises capital letters, lower-case letters, Arabic figures, the dollar-mark, 10 the pound-sterling mark, and the ordinary punctuation-marks.

The capital letters are vertical and quite broad in proportion to their height and their shaded portions are very wide in comparison 15 with the unshaded. They are without cer- iphs. The angle of the letter A is quite open and the characteristic cross-stroke is very near the bottom of the letter. Because of the extreme thickness of its shaded portions it 20 has almost a one-sided look, and the same is true of the letter M, in which the right-hand thick-shaded portion occupies nearly one-third of the width of the letter. The characteristic horizontal strokes of the capital let- 25 ters E, F, and H are above the middle of the letter, the horizontal strokes of the letter E and the upper stroke of F being of the same width throughout, the characteristic horizontal stroke of the capital letter F broadening 30 out toward its extremity, and the horizontal stroke of the capital letter H representing a circumflex accent, being narrow at each end and broad at the middle and having a slight curve, after the manner of that accent. The 35 lower terminal stroke of capital C and the upper terminal stroke of capital G are quite slender, the lower extremity of the capital G being substantially rectangular in form and extending considerably above the middle of 40 the letter. The loops of the capitals P and R extend from the top considerably below the middle of the letter, the characteristic lower terminal of capital R being nearly horizontal, somewhat curved, and terminating in a point.

45 The lower terminal of the capital J is a loop of which the horizontal portion is quite narrow, the terminal itself curving back upon the letter somewhat and broadening out, being cut off in a line forming an acute angle 50 with the vertical line of the letter. The upper curve of the capital S is quite narrow and the letter swells out to a considerable extent

below it, and its lower terminal being quite thin. The right-hand shaded portion of the letter W is in the form of a diamond which 55 touches the left-hand shaded portion, the upper right-hand terminal of said letter being a narrow line extending into the right-hand lower edge of said diamond.

The vertical and shaded lines of the lower- 60 case letters have substantially the same heavy characteristic as the upper case, though in a less marked degree, the shaded portions of these letters being somewhat less wide in pro- 65 portion than the shaded portions of the up- per case.

The stems of the lower-case letters b, d, f, h, 70 k, l, p, q, and t are quite long in proportion to the body of the letter, are rectangular at their extremities, and because of their width 75 they make these letters appear somewhat out of proportion in size to the rest of the lower case. The bulbs or loops of the letters b, d, g, h, m, n, p, q, r, and u curve inward, where 80 they join the vertical line. The letter s is 75 similar to the capital S, being very much wider at the bottom than at the top. The stems of the letters g, j, and y, not forming a portion of the shaded part of the letter, are 85 rather insignificant in appearance, the g and j curving backward slightly and tapering sud- 90 denly off to nearly a point, the y, however, broadening out at its lower extremity. The stem of the lower-case p extends about an equal distance above and below the loop. 85 The lower-case l is a rectangle, as is also lower- 95 case t, the characteristic cross-line of the lat- eter being light and slightly above the middle of the letter. The right-hand terminal of the lower-case v and w has a reverse curve and 100 terminates in a dot.

The numerals are all of the same height, their shaded portions having the same char- 95 acteristic as the shaded portions of the rest of the font—that is, being considerably wider than the unshaded portions; but with the exception of the numerals 1 and 4 they are curved somewhat, so that they do not present the somewhat angular effect which charac- 100 terizes the letters of the font. The numeral 3, for example, consists of two curves joining above the middle of the figure, the vertical portion of the figure being very broad and the lower terminal turning in upon the figure

somewhat, being cut off in a line at an angle to the vertical line. The figure 4 consists of a broad vertical stroke having a narrow angular portion upon its left-hand side. The numeral 8 is formed of two o's, one resting upon the other, the lower one being considerably larger than the upper one. The lower terminal of the figure 9 is very thin in comparison with the shaded portion thereof. The pound-
sterling character has a slight backward slant. The points of the punctuation-marks are circular and the marks themselves are quite

heavy except the dash, which, like the other horizontal marks in the font, is quite narrow.

What I claim as my invention is—

The design for a font of type herein shown and described.

In testimony whereof I have hereunto set my name this 23d day of December, 1898.

JOSEPH W. PIINNEY.
